The ornamental design for an electrical connector housing, substantially as shown and described.

DESCRIPTION

FIG. 1 is an end elevational view of an electrical connector housing showing my new design; FIG. 2 is a side elevational view thereof; and FIG. 3 is a perspective view thereof.

The broken lines of FIGS. 1 and 3 represent openings through one end of the connector, but form no part of the design.

The end opposite that shown in FIG. 3 is unornamented.
